(57) **CLAIM**

The ornamental design for a shingle cutting device as shown and described.

DESCRIPTION

FIG. 1 is a top perspective view of a shingle cutting device showing the new design.

FIG. 2 is a bottom perspective view of a shingle cutting device showing the new design.

FIG. 3 is a top view of a shingle cutting device showing the new design.

FIG. 4 is a bottom view of a shingle cutting device showing the new design.

FIG. 5 is a front view of a shingle cutting device showing the new design.

FIG. 6 is a rear view of a shingle cutting device showing the new design.

FIG. 7 is a first side view of a shingle cutting device showing the new design; and,

FIG. 8 is a second side view of a shingle cutting device showing the new design.

1 Claim, 6 Drawing Sheets
